UNITED STATES PATENT OFFICE.

ELMER E. KAUFMAN, OF SCRANTON, PENNSYLVANIA.

THREAD GUIDE FOR REWINDING MACHINES.

Application filed February 21, 1922. Serial No. 538,330.

To all whom it may concern:

Be it known that I, ELMER E. KAUFMAN, a citizen of the United States, and a resident of Scranton, in the county of Lackawanna and State of Pennsylvania, have invented a new and Improved Thread Guide for Rewinding Machines, of which the following is a full, clear, and exact description.

This invention relates to thread guides for re-winding machines and has for an object to provide an improved construction over my co-pending application, Serial No. 515,754, the structure being such that the guide may be used on old or new spindles. Another object of the invention is to provide a guide utilizing a removable knob as the retaining means therefor.

A further object, more specifically, is to provide a simple construction for holding a thread guiding structure in place which may be applied to spindles of different sizes and removed readily without injuring the spindles.

In the accompanying drawing—

Figure 1 is a top plan view of a guide, spindle, spool and associated parts shown in operative position.

Figure 2 is a side view of the structure shown in Figure 1.

Figure 3 is a vertical sectional view through the supporting knob shown in Figure 2.

Referring to the accompanying drawing by numerals, 1 indicates a spool of any desired kind containing a supply of thread or yarn 2, said spool being mounted on the spindle 3 which spindle is usually tapering. This construction of spool and spindle are old and well known in re-winding machines as well as other machines. In connection with the thread 2 it is necessary that the same be guided from the spool 1 so that it will always leave a certain point. In order to do this, a guiding structure 4 is provided which is formed usually with two arms 5 and 6, said arms at the ends having one or more turns 7 whereby eyes are provided through which the thread 2 may pass. In the drawing, only one of these eyes has been shown in use.

The guiding structure 4 may be made from any suitable wire or other material and bent at the respective points 8 to form upstanding sections 9, said upstanding sections being bent at 10 and merging into

slanting or entrance sections 11 which entrance sections merge into a looped structure 12. The inner ends of the entrance sections 11 approach each other to the greatest extent at points 13 and 14 whereby a restricted neck is produced. This neck is of less distance in diameter than the supporting knob 15 at the bottom of the groove 16. The groove 16 is annular and, therefore, provides shoulders 17 and 18 for supporting the guiding structure 4. A bore 19 is provided centrally of the knob, said bore tapering whereby it may be mounted on spindles of different sizes and at the same time be forced tightly into position for properly supporting the guiding structure 4.

This knob may be made of metal, wood or other material and may be quickly applied and removed without injury to the spool or to the knob. Heretofore, more or less complicated structures have been used for supporting thread guiding means or else a groove has been provided as shown in my co-pending application, which groove is objectionable in that it requires the spindle to be taken down and a groove formed therein unless originally constructed in that manner. By the use of the knob 15 the same result is secured, namely, the proper supporting of the thread guiding structure 4 while the spindle is not mutilated and the knob may be applied and removed at any time for different sized spindles within the limits of the bore 19.

What I claim is:—

In a thread guide for re-winding machines, the combination with a supporting knob having an aperture extending therethrough and an annular groove arranged in a plane at right angles to the aperture, of a thread guide co-acting with said knob and fitted into said groove comprising a single element bent adjacent its center to form a resilient ring adapted to be loosely positioned in said groove, said ring merging into projecting portions positioned nearer to each other than the diameter of the ring, said projecting portions merging into side arms bent laterally and rearwardly toward said ring and then diametrically outwardly to present arms, and a twisted structure at the ends of said arms forming thread guiding eyes.

ELMER E. KAUFMAN.
